WILLIAM E. SMITH, OF MILLTOWN, NEW JERSEY, ASSIGNOR TO KILBOURN MANUFACTURING CORPORATION, OF NEW BRUNSWICK, NEW JERSEY, A CORPORATION OF NEW JERSEY.

CIRCULAR-KNITTING MACHINE.

1,145,931.

Specification of Letters Patent. Patented July 13, 1915.

Application filed July 13, 1914. Serial No. 850,545.

To all whom it may concern:

Be it known that I, WILLIAM E. SMITH, a citizen of the United States, residing at Milltown, in the county of Middlesex and 5 State of New Jersey, have invented certain new and useful Improvements in Circular-Knitting Machines; and I do hereby declare the following to be a full, clear, and exact description of the invention, such as 10 will enable others skilled in the art to which it appertains to make and use the same.

My invention consists in the novel features hereinafter described, reference being had to the accompanying drawing which 15 illustrates several embodiments of my invention, selected by me for purposes of illustration, and the said invention is fully described in the following description and claims.

20 Referring to the drawings, Figure 1 represents a partial sectional view of a type of knitting machine for knitting seamless stockings, provided with a stationarily supported rotatable cam cylinder and vertically 25 adjustable needle cylinder, and having my improved invention embodied therein. Fig. 2 represents an elevation of a portion of the interior of the cam ring showing the knitting cam. Fig. 3 is a top plan view of the 30 same. Fig. 4 is a section on line 4-4 of Fig. 3. Fig. 5 is a similar sectional view showing a slightly modified construction. Fig. 6 is a diagrammatic representation of the stocking designed to be knit by my invention. Fig. 7 is a sectional view on line 35 7-7 of Fig. 6. Fig. 8 represents a partial sectional view of a type of knitting machine having a rotating needle cylinder and a stationery but vertically adjustable cam cylinder 40 having my invention embodied therein. Fig. 9 is a top plan view of a portion of the machine illustrated in Fig. 8, a part being broken away. Fig. 10 is a diagrammatic view representing the cam cylinder of the 45 machine shown in Figs. 8 and 9 as it would appear if spread out in a single plane. Fig. 50 11 is an enlarged view of the central portion of Fig. 10. Fig. 12 is a vertical section on line 12-12 of Fig. 11. Fig. 13 is a view 55 similar to Fig. 11, showing the relative positions of the parts when the cam cylinder has been raised above the position indicated in Fig. 11. Fig. 14 is a vertical section on line 14-14 of Fig. 13. Fig. 15 is a detail view of one of the long needles provided

with the long nib which knit the front portion of the leg and top of the foot of the stocking. Fig. 16 is a detail view of one of the short needles provided with a short nib which knit the rear part of the leg, the sole, 60 and the heel and toe pocket.

My present invention has special applicability to the knitting of a circular knit stocking invented by Edward E. Kilbourn, William E. Smith, and Isaac W. Kilbourn, 65 in which the stitches throughout the sole portion of the foot of the stocking are increased in size beyond that of the stitches forming the top portion of the foot in the corresponding courses, sufficiently to make 70 the sole portion of the foot a size or more longer as well as wider than the top portion of the foot of the stocking for the purpose of fashioning the stocking to fit the foot. The stocking itself, therefore, forms 75 no part of the present invention.

The object of my present invention is to provide mechanism for knitting the stocking hereinbefore referred to upon a circular 80 knitting machine provided with a single cam cylinder, and to this end, it consists in the novel features hereinafter described.

In carrying out my invention, I provide a circular knitting machine of the kind described having only one cam cylinder for 85 operating all of the needles of the circular series with two sets of needles, one of which knits the top portion of the foot, or that portion of the tube which is composed of 90 tight stitches or what I may term normal stitches such as are used in the leg and top of the foot, and the other set of needles is employed to knit the sole of the foot of the stocking with a materially larger stitch, but which also must be capable of knitting the 95 rear portion of the leg of the stocking with the same tight stitch that is employed in the front portion of the leg. The needles of one series are made of greater length from the cam engaging nib to the hook portion thereof than the other set and the needles of one series are provided with nibs of different length from the nibs of the needles of the other series and the cam cylinder is provided with a knitting cam formed of two 100 sections at different distances from the circle of the needles, the inner cam section engaging only the short nibs, and the outer cam engaging the long nibs, one of the cam sections being capable of being adjusted ver 105 110

tically with respect to the other. It follows from this construction that if the nib engaging faces of the two cam sections are made to coincide as to draw down the 5 needles of both sets to the same extent the shorter needles will of necessity draw the thread a greater distance below the nosing or the sinkers or other support for the knitted fabric, than the longer needles, and 10 will thus produce stitches of larger gage than are produced by the longer needles. It will also be seen that by adjusting that portion of the cam which operates the shorter needles so that they are drawn down a less 15 distance corresponding to the difference in the length of the two sets of needles, both sets of needles will draw the same length of stitch, that is to say, the normal or tight stitch.

20 In the specific embodiment of my invention herein shown in Figs. 1 to 4 inclusive, of the drawings, A represents a needle cylinder provided with the usual needle grooves to receive a series of needles B, one of which 25 is shown in Fig. 16, which knit the back of the leg, the sole of the foot, and the heel and toe pockets, and a second series of needles B', one of which is shown in Fig. 15, which knit the front of the leg and top 30 of the foot. The series of needles B may be equal in number to the series of needles B' or not as preferred, it being understood that the two series of needles complete the circular series necessary for the formation of 35 the knitted tube. Each of the needles B is provided with a short nib b and each of the needles B' is provided with a longer nib b', and the needles B' are of greater length from the nib b' to the hook, than the 40 distance from the nib b to the hook of the needles B, the increase in length of the needles B' being sufficient to enable the needles B which knit the sole of the stocking, to draw down their stitches a sufficiently 45 greater distance than the needles B', to make these stitches through the sole of sufficiently greater size to make the sole portion of the stocking a size or more longer than the corresponding top portion knit 50 by the needles B', when the nibs of the needles are drawn down to the same point in the needle cylinder, the long sole portion being correspondingly increased in width. C represents the cam cylinder, which is provided with a cam groove c and with a duplex knitting cam c', c², and a riser cam c³. The knitting cam comprises an exterior fixed portion c² ordinarily secured to the cam cylinder, and an interior movable portion c' 55 capable of vertical movement with respect to the fixed portion c² and in this instance being provided with screws d' extending through vertically disposed slots d² in the wall of the cam cylinder and connecting the movable portion c' of the knitting cam with

a slide d on the exterior of the cam. S represents the usual sinker ring and s the sinkers supported between the needles by means of a nosing N which is preferably capable of slight vertical adjustment with respect to the cam cylinder C, in any usual or preferred way. Suitable means are provided for rotating the needle cylinder with respect to the cam ring or the cam ring with respect to the needle cylinder, as preferred, 75 and in this instance, the cam C is shown as rotatable and is provided with a driving gear c⁴ engaged by a gear G for imparting motion thereto.

In knitting the leg of the stocking in 80 which it is desired that all of the needles shall draw the same length of stitch, to wit, the normal or tight stitch, the adjustable portion c' of the knitting cam, which as will be seen, operatively engages only the short 85 nibs b of the short needles B, will be set at its highest position, with its nib engaging face above that of the stationary portion c² of the cam. If now, the cam cylinder C is rotated, a complete circular course of knitting will be produced, thread being supplied to the entire circular series of needles in any usual or well known way, and it will be noted that the longer needles B' will be operated upon only by the fixed portion c² 90 of the knitting cam, while the short needles B will be operatively engaged only by the movable portion c' of the knitting cam and will therefore be drawn down to a less extent below the sinkers so that both sets of 95 needles will be drawn down to the same point below the sinkers and will draw the same length stitch, to wit, the tight or normal stitch. When it is desired to knit the longer stitches on the needles B, the movable 100 portion c' of the knitting cam is depressed either by hand or automatically under the control of suitable pattern mechanism in a well known way so that its nib engaging portion will be made to coincide with that 105 of the fixed portion of the cam, and thereupon, on the rotation of the cam cylinder for circular work, as in knitting the foot portion of the stocking, the needles B which 110 knit the sole portion will have their short nibs carried down to the same point as the long nibs b' of the needles B' and as the needles B are shorter than the needles B', the hooks of the needles B will be carried a greater distance below the sinkers than 115 the hooks of the needles B', thus drawing 120 stitches of materially increased size and of sufficiently greater size to make the sole portion of the stocking a size or more longer than the corresponding courses of the top 125 of the foot. If it is desired to reinforce the sole of the stocking to partially fill the large stitches forming the same, a reinforcing thread may be employed or the sole portion of the stocking may be knit with a 130

heavier thread than the top portion of the foot. In Fig. 6 I have shown a side view of the stocking referred to, in which 1 represents the leg, and 2 the top of the foot, both 5 knit with a tight stitch. 3 represents the heel pocket and 5 the toe pocket knit in the usual manner by narrowing and widening by reciprocating work, and preferably as a heavier fabric, and 4 represents the elongated 10 fashioning sole which, as before stated, is knit with sufficiently larger stitches to make the sole actually a size or more longer and wider than the corresponding courses of the top of the foot.

15 In Fig. 7 I have shown diagrammatically a cross sectional view through the foot portion of the stocking in which the stitches *a* in the courses forming the top of the foot are knit by the needles *B'* with the ordinary 20 tight stitch, while the stitches *b²* in the courses forming the sole portion of the foot are knit by the needles *B* and are of greater size than the stitches *a*, thus making the sole portion of the foot not only longer, but 25 wider than the corresponding portion of the top of the foot, even though the same number of needles are employed in knitting both parts of the foot, the line of division being indicated by the dotted line *x*—*x*.

30 In case a slight adjustment of both the normal or tight stitches and a corresponding adjustment of the large stitches should be necessary to accommodate the machine for using yarns of different size or thickness, 35 this may be accomplished by vertically adjusting the nosing or the supports for the sinkers, with respect to the knitting cam, without affecting the operation of my apparatus or the relative difference in size between the normal or tight stitch and the enlarged 40 stitch for the sole portion of the stocking. This may be accomplished in many ways, for example, as shown in Fig. 1, the cylinder is supported upon a ring *R*, exteriorly threaded and engaging a threaded aperture in the bed of the machine, and by 45 adjusting this ring, the needle cylinder may be adjusted vertically with respect to the cam cylinder to slightly vary the size of the 50 stitches as desired.

In Figs. 8 to 14 inclusive, I have shown my invention embodied in a knitting machine of slightly different type and also well known in the art, in which the knitting 55 cylinder *A'* is supported upon a rotating plate *A²* provided with means for imparting rotary and reciprocating movement to the cylinder, said plate being, in this instance, provided with a gear *A³* meshing with a 60 beveled gear *G'* to which power may be applied in a well known way and preferably under the control of pattern mechanism, to rotate the cylinder during circular work, and to reciprocate it during reciprocating 65 work, and narrowing and widening, for the formation of heel and toe pockets. *C'* represents the cam cylinder, which in this type of machine, does not rotate and is supported so as to be vertically adjustable. In this instance, the cam cylinder *C'* is supported 70 upon a plate *C²*, a portion of which extends around the needle cylinder, and said plate is supported upon the upper end of a vertically adjustable column *C³* which can be adjusted vertically, preferably under the 75 control of pattern mechanism in a well known way. The main portions of this type of machine, including the parts above referred to, are so well known to those skilled in the art that a particular illustration and description of the same is deemed unnecessary to a clear understanding of my invention as applied thereto. The needle cylinder *A'* is provided with a series of consecutive needles *B*, provided with the short nibs 80 *b*, such as illustrated in Fig. 16, for knitting the rear portion of the leg, the sole and the heel and toe pockets of the stocking, and the remaining consecutive tricks of the needle cylinder are provided with longer nibs *b'*, 85 provided with the longer nibs *b'*, such as are illustrated in Fig. 15, there being preferably, but not necessarily, substantially the same number of each kind of needles, 90 and the needles *B* are sufficiently shorter than the needles *B'* as hereinbefore stated, so that when both sets of needles are drawn down to the same extent, the short needles *B* will draw sufficiently longer stitches when 95 knitting the sole of the stocking to make the fabric of the sole a size or more longer and correspondingly wider than the fabric formed by the corresponding courses of the top of the foot. This machine, like the machine previously described, has only one 100 cam cylinder, which is provided with a stitch forming cam formed of two parts *c⁴* and *c⁵*, which alone act to draw down the needles during circular work and act in conjunction with the riser cam *c⁶* adjacent thereto, the two cam sections *c⁴* and *c⁵* being arranged at different distances from the center of the needle cylinder and the cam section *c⁴* being adapted to engage the short 105 nibs, *b*, only, of the needles *B*, while the outer cam section *c⁵* is constructed to engage the long nibs *b'* of the needles *B'*. The cam cylinder is also provided with an additional knitting cam *c⁷* operating in conjunction 110 with a riser cam *c⁸* when the needle cylinder is reversed during the alternate reciprocations of reciprocating work. The inner cam section *c⁴*, as well as the additional knitting cam *c⁷*, are usually supported from the vertically adjustable cam plate *C²* by means of 115 arms or brackets *c⁹* and *c¹⁰* respectively, and a central cam *c¹¹* between and above the knitting cams, is also supported from the plate *c²* by means of a plate or bracket *c¹²*. The outer cam section *c⁵* is supported in fixed re- 120 125 130

lation vertically with the needle cylinder in order that the relative positions of the cam sections c^4 and c^5 may be varied in a vertical direction, and to this end I have shown the 5 outer cam section c^5 supported from the bed plate P of the machine, by means of a bracket arm p so that the cam section c^5 which lies behind or outside of the cam section c^4 , remains stationary while the cam 10 cylinder and cam plate may be raised and lowered by means of the vertically adjustable column C⁸.

When it is desired to knit a tubular portion of the fabric in which all of the stitches 15 are to be uniform, as for example, the leg portion of the stocking, which is to be knit with a tight stitch, the cam plate C² and cam cylinder C' are moved to the position indicated in Fig. 13, that is to say, the cam 20 cylinder C' is raised sufficiently from the bed plate P to elevate the inner cam section c^4 so that its nib engaging face is as far above the nib engaging face of the outer cam section c^5 as the needles B' exceed in 25 length the needles B. The parts being in this position when the needle cylinder is rotated, the long needles will be drawn down by the outer cam section c^5 as usual, and the short needles B will be drawn down by the 30 inner cam section c^4 to a sufficiently less extent, as will be readily understood, so that the two sets of needles will draw stitches of equal length, to wit, the normal or tight stitches. In knitting the long fashioning 35 sole of the stocking, the cam cylinder C' will be lowered until the position indicated in Fig. 11, so as to bring the nib engaging faces of the inner and outer cam sections c^4 and c^5 into registration and in knitting the 40 sole of the stocking therefore, the long and short nibs will both be drawn down to the same point, thus carrying the hooks of the shorter nibs b farther below the nosing than the hooks of the long nibs B', which still 45 draw the same stitch as before, so that the short needles will draw a longer stitch than the long nibs, the stitches formed by the short needles being sufficiently longer to 50 make the sole portion of the stocking a size or more longer and wider than the corresponding courses of the top of the foot. The heel and toe pockets will be formed of reciprocating work in the usual manner in 55 which they are formed in this type of machine, which is well understood by those skilled in the art, and need not be herein specifically described.

I am aware of the fact that a cam ring 60 has been heretofore provided with a fixed and movable portion for an entirely different purpose or purposes, in connection with needles having the same length from their nibs to the hooks thereof, but I am not aware that such a cam has ever been employed in combination with needles having

different length nibs, the needles having one length of nib being of a predetermined length and the needles having the other length nib having a different length from the nib to the hook portion thereof, as hereinbefore described, and for the purpose hereinbefore set forth. 70

It will be understood that in knitting a circular knit stocking in accordance with my improved invention the heel and toe 75 pockets will be made by narrowing and widening in the usual and well known manner, and I have therefore not herein described or shown the narrowing and widening mechanism or the operation thereof. 80

What I claim and desire to secure by Letters Patent is:—

1. In a circular knitting machine, the combination with a circular series of needles, the successive needles for knitting one portion of the tubular fabric being of greater length between the operating nibs thereof and their thread engaging hook portions than the consecutive needles for knitting the other portions of the tubular fabric, and 90 adjustable needle actuating means for drawing down said needles to the same extent when knitting a portion of the knitted tube, and to different extents when knitting other portions of the knitted tube. 95

2. In a circular knitting machine, the combination with a circular series of needles, the successive needles for knitting one portion of the tubular fabric being of greater length between the operating nibs thereof and their thread engaging hook portions than the consecutive needles for knitting the other portions of the tubular fabric, the said long and short needles having respectively nibs of different lengths, and needle 100 actuating means comprising a knitting cam for engaging the longer nibs and a separate cam for engaging the shorter needle nibs, one of said cams being vertically adjustable with respect to the other. 110

3. In a circular knitting machine, the combination with a circular series of needles, the successive needles for knitting one portion of the tubular fabric being of greater length between the operating nibs thereof and their thread engaging hook portions than the consecutive needles for knitting the other portions of the tubular fabric, the needles of one length having longer nibs 115 than those of the other length, needle actuating mechanism comprising a single cam cylinder, of a pair of separate knitting cams carried thereby and located at different distances from the circular series of needles, for actuating the long and short 120 nib needles respectively, and one of said cams being vertically adjustable into and out of registration with the other. 125

4. In a circular knitting machine, the combination with a circular series of needles, 130

consecutive needles of said series for knitting the front of the leg and top of the foot of the stocking being of greater length from their actuating nibs to the hook portions thereof than the consecutive needles for knitting the back of the leg and sole of the stocking, the said longer needles having longer nibs than those of the shorter needles, of needle actuating mechanism comprising a single cam cylinder provided with an inner knitting cam for engaging the short nib needles and an outer knitting cam for engaging the long nib needles, and means for varying the vertical position of said inner knitting cam with respect to the outer knitting cam, and the needles.

5. In a circular knitting machine, the combination with a circular series of needles, consecutive needles of said series for knitting the front of the leg and top of the foot of the stocking being of greater length from

their actuating nibs to the hook portions thereof than the consecutive needles for knitting the back of the leg and sole of the stocking, the said longer needles having longer nibs than those of the shorter needles, of needle actuating mechanism comprising a single cam cylinder provided with an inner knitting cam for engaging the long nib needles, means for holding the outer cam stationary with respect to the needles, and means for elevating and depressing the inner cam to bring its nib engaging face out of and into registration with the nib engaging face of the other cam.

In testimony whereof I affix my signature, in the presence of two witnesses.

WILLIAM E. SMITH.
